The ornamental design for a pressure sensor, as shown as described.

(51) **LOC (7) Cl.** ..... **10-04****DESCRIPTION**(52) **U.S. Cl.** **D10/85**

FIG. 1 is a front perspective view of a pressure sensor showing my new design;

(58) **Field of Search** D10/83, 85; 73/273,

FIG. 2 is a top plan view thereof;

73/431, 756, 708, 718, 724, 61.42, 730,

FIG. 3 is a left side elevational view thereof;

19.03, 19.1; 91/445-448, 454; 324/204

FIG. 4 is a right side elevational view thereof;

(56) **References Cited**

FIG. 5 is a bottom plan view thereof;

U.S. PATENT DOCUMENTS

FIG. 6 is a front elevational view thereof; and,

5,177,993 A * 1/1993 Beckman et al. 73/19.03

FIG. 7 is a rear elevational view thereof.

D371,085 S * 6/1996 Ito D10/85

The broken lines shown in FIGS. 1-7 are for illustrative purposes only and form no part of the claimed design.
